DISPENSING CONTAINER

John S. Forster, Pittsburgh, Pa., assignor of one-half to Raymond Schmidt, Pittsburgh, Pa.

Application February 25, 1935, Serial No. 7,969

3 Claims. (Cl. 221—60)

The invention relates generally to dispensing containers and more particularly to the collapsible type of dispensing containers.

The object of the invention is to provide a collapsible dispensing container with a closure that is dependable, easy to operate and that may be economically manufactured.

The invention accordingly is disclosed in the embodiment thereof shown in the accompanying drawing and comprises the features of construction, combination of elements, and arrangement of parts, which will be exemplified in the construction hereinafter set forth and the scope of the application of which will be indicated in the claims.

For a fuller understanding of the nature and objects of the invention, reference may be had to the following detailed description, taken in connection with the accompanying drawing, in which:

Figure 1 is a view, partly in section and partly in side elevation, showing a dispensing container constructed in accordance with my invention, with the parts in unassembled arrangement,

Fig. 2 is a view, partly in section and partly in side elevation of the upper end of a dispensing container showing the structure after it has been assembled,

Fig. 3 is a view similar to Fig. 2, showing the closure member in a different position, with the opening therein in alignment with the opening in the top of the container,

Fig. 4 is a view, partly in section and partly in side elevation of the upper end of a dispensing container showing a modification of the closure member,

Fig. 5 is a view in section showing the upper part of a dispensing container similar to that illustrated in Fig. 4, but with the closure member disposed in its open position, and

Fig. 6 is a view in vertical section of a closure member similar to that shown in Figs. 2 and 3, illustrating a different method of connecting the neck to the top of the container.

Referring now to the drawing, and Figs. 1 to 3 in particular, the dispensing container comprises a tube 10 carrying a top 11 which is provided with a neck 12. In constructing a container of this kind, it is preferable to use a metal such as tin or aluminum which may be readily extruded. While these metals are suitable, and have been widely used for constructing such dispensing containers, when it is desired to use the container for materials which will react with these metals,

any other suitable material such as alloys or other metals may be substituted.

The common practice in constructing collapsible containers from tin or aluminum is to extrude them. The container such as I have introduced lends itself very readily to extruding. In extruding these tubes, they are made with the lower end of the tube 10 open. This open end of the tube may be closed by collapsing the lower end of the tube to provide meeting edges and then crimping it in a manner well known in the art, and so it has been deemed unnecessary to illustrate the crimped end.

As illustrated in Figs. 1 to 5, inclusive, the top 11 and neck 12 are made integral. A seat 13 is provided between the top 11 and neck 12. The size of the seat 13 will depend on the size of the closure member it is desired to use and which will be described hereinafter. As illustrated, the seat is substantially conical in shape or it may be said that it simulates the surface of a conic frustum.

An opening 14 is provided in the top 11 through which materials stored in the tube may be extruded. Generally the opening is disposed centrally of the neck 12 and tube 10.

A notch 15 is provided in the neck 12 to receive the actuating member provided for operating the closure member to be described hereinafter. The notch 15 will be located in accordance with the design of the closure member.

A washer 16 made from some suitable resilient material such as cork is disposed in the neck in alignment with the seat 13. The size of the washer will depend on conditions to be met.

A closure member 17 which is substantially spherical in shape is disposed in the neck 12. As illustrated, the closure member is made of such a size that it will just snugly fit within the neck 12. It is preferably made from the same metal as the tube 10.

An opening 18 is provided in the closure member 17. While in this embodiment the opening 18 is illustrated as circular in cross-section, other shapes may be employed. The size of the opening 18 will depend upon the material that is to be dispensed from the container and other conditions that are generally taken into account when designing such tubes. The edges defining the opening 18 are slightly flattened or rounded so that they will not cut the washer 16.

In the modification illustrated in Figs. 1 to 3, inclusive, an eye member 19 is provided on the closure member 17. This eye member is disposed at right angles to the axis of the opening 18.

through the closure member and midway between the ends of the opening. This eye member has a double function. It may be employed for actuating the closure member to align the opening 18 with the opening 14 in the top 11, or it may be used for hanging the dispensing container on a hook or other support when not in use.

In assembling the dispensing container, the closure member 17 is pressed downwardly into the neck forcing the washer 16 into tight engagement with the seat 13. The wall of the neck 12 is then bent inwardly, engaging the closure member to hold it in position.

It may be desirable in assembling the dispensing container to press the closure member into the cork washer to give more than a line contact. By pressing the closure member downwardly, it is caused to engage the washer over an area simulating a hollow circle, thus producing a good tight closure.

Assuming the closure member stands in the position illustrated in Fig. 2, and it is desired to set the closure member to permit the extrusion of the contents of the tube, then the eye member 19 is rotated through a ninety degree angle to the position illustrated in full lines in Fig. 3. The opening 18 in the closure member is then aligned with the opening 14 in the top 11 and the contents may be extruded in the usual manner by collapsing a portion of the tube.

When it is desired to close the tube, the eye member 19 is merely rotated to the vertical position again and then rotated about the vertical axis carrying the opening 18 to a point out of alignment with the notch 15. When the tube has been closed in this manner, it cannot again be opened until the closure member 17 is rotated about two axes. Therefore a very dependable closure is provided.

In the modification illustrated in Fig. 4, a ring 20 is provided on the closure member 17 instead of the eye member described in connection with the structure shown in Figs. 1 to 3, inclusive. In this modification, two notches 15 are provided in the neck 12.

In the structure illustrated in Fig. 4, the closure member is opened by swinging the ring 20 to the position illustrated in Fig. 5. In this manner the opening 18 in the closure member is aligned with the opening 14 in the top 11. To close the tube the ring 20 is merely swung into the vertical position again.

In the modifications shown in Figs. 1 to 5, inclusive, the closure member is formed integral with the tube 10. In the modification illustrated in Fig. 6, a slightly different construction is employed. As illustrated, the neck 12 is made longer, presenting a hollow cylindrical portion below the seat 13. This extension of the neck is threaded internally as shown at 21. When the closure is made in this way, the body of the tube 22 is made with a threaded neck 23. In such a construction in assembling, the closure member is merely screwed onto the threaded neck of the tube. Such a construction has advantages in that each closure member may be used with a number of tubes.

Since certain changes may be made in the above invention and different embodiments of the invention made without departing from the scope thereof, it is intended that all matter contained in the above description or shown in the

accompanying drawing shall be interpreted as illustrative and not in a limiting sense.

It is also to be understood that the following claims are intended to cover all of the generic and specific features of the invention herein described, and all statements of the scope of the invention which, as a matter of language, may be said to fall therebetween.

I claim as my invention:

1. A dispensing container comprising in combination, a collapsible tube closed at one end, a top provided on the other end, the top having an opening extending therethrough, a hollow cylindrical neck provided on the top, a seat provided between the neck and top, the seat simulating a surface of a conic frustum inverted, a cork washer disposed in the neck, a substantially spherical closure member having a discharge opening extending therethrough disposed in the neck, the closure member pressing the washer tightly against the seat, means for retaining the closure member in engagement with the cork washer, an eye member carried by the closure member providing means for operating it, the eye member being disposed at right angles to the opening through the closure member and midway between the ends of the opening, the neck having a U-shaped notch therein to permit the operation of the eye member to rotate the closure member to set the opening therethrough in alignment with the opening in the top.

2. In a dispensing container in combination, a hollow cylindrical neck portion, a seat in the lower end of the neck portion, the seat simulating the surface of a conic frustum inverted, a cork washer mounted on the seat and a substantially spherical closure member having an opening therethrough disposed in the hollow cylindrical neck engaging the washer throughout the area of an annulus located within the boundaries of the washer and pressing it into tight engagement with the seat thus providing a good closure, means for actuating the closure member to align the opening therein with the axis of the neck, and means for connecting the neck portion to a container.

3. In a dispensing container in combination, a hollow cylindrical neck portion, a seat in the bottom of the neck portion, the seat simulating the surface of an inverted conic frustum, a cork washer disposed in the neck above the seat, a substantially spherical closure member having an opening therethrough disposed in the hollow cylindrical neck engaging the washer throughout the area of an annulus lying within the boundaries of said washer and pressing it tightly into engagement with the seat thus providing a good closure, the wall of the outer end of the neck extending inwardly engaging the closure member to retain it in position, an eye member carried by the closure member, the eye member being disposed at right angles to the axis of the opening through the closure member and substantially equally spaced from the ends of said opening, the neck portion having a notch cut in its wall to permit a movement of the eye member to a predetermined position to open the tube, and means for connecting the neck to a container.

JOHN S. FORSTER. 70
